UNITED STATES PATENT OFFICE.

WILLIAM T. PRINGLE, OF PHILADELPHIA, PENNSYLVANIA, ASSIGNOR TO V. V. FITTINGS COMPANY, OF PHILADELPHIA, PENNSYLVANIA, A CORPORATION OF PENNSYLVANIA.

ELECTRIC SWITCH.

Application filed April 9, 1919. Serial No. 288,806.

To all whom it may concern:

Be it known that I, WILLIAM T. PRINGLE, a citizen of the United States, residing in Philadelphia, Pennsylvania, have invented 5 Electric Switches, of which the following is a specification.

One object of my invention is to provide a novel combination of electric switching apparatus and container whereby the latter is maintained in a closed condition, preventing access to the switching apparatus, until the switch operating element has been moved to such a position as to open the switch and thus cut off current from part 15 of said apparatus and from the line or electroreceptive device connected thereto; the invention further contemplating such an arrangement of parts as will prevent the switch being closed as long as the container 20 is open.

Another object of my invention is to provide a novel combination of switch operating member and closed container in which is mounted a switch actuated by said member, whereby the latter may be moved 25 at will to open or close the switch as long as the closure is in such position as to prevent access to said switch or to certain conductors connected thereto, but will be held from movement after being brought 30 to a position in which the switch is open, as long as or whenever the closure occupies any other position.

Another object of my invention is to provide a novel construction of container closure formed with an opening in which a switch operating member shall be freely movable as long as the closure is in position to prevent access to the switch or its associated conductors; the invention contemplating also a combination of switch operating member and container whereby when the former has been moved to such 45 position as to permit shifting of the closure to expose the interior of the container, said member will be retained in this position until the closure member has been again moved into position to allow of the operating member being entered in and moved 50 through said opening of this cover.

These objects and other advantageous ends I attain as hereinafter set forth, refer-

ence being had to the accompanying drawings, in which,

Figs. 1 and 2 are perspective views illustrating a switch box and part of its enclosed apparatus constructed in accordance with my invention, the first of these views showing the box closed and the second illustrating it with its closure or cover in 60 the open position;

Fig. 3 is a plan of the apparatus shown in Figs. 1 and 2;

Fig. 4 is a longitudinal vertical section, partly in side elevation, further illustrating 65 the invention; and

Fig. 5 is an inverted plan, partly in section on the line 5—5, Fig. 4.

In the above drawings, 1 represents a box of generally rectangular section, having a 70 cover 2 in the form of a flat plate pivotally connected to it at one corner by a screw or bolt 3 whereby it is left free to swing in its own plane, i. e.,—the plane of the top or open side of the box, within certain 75 definite limits defined by stops hereafter referred to. Said box, at the upper corner of one side, is provided with a perforated lug 4, designed to cooperate with a second and similar lug 5 carried at one corner of 80 the cover, for the reception of a padlock whereby said cover may be retained in a position closing the opening into the box. Said first lug also serves to limit movement of the cover in one direction so that at the 85 end of such movement it lies over and closes the otherwise open face of the box.

Within the switch box is mounted an insulating slab or base 6 of marble, slate or the like, preferably lying in a plane parallel with the cover, and in the case illustrated, spaced away from the same by a distance somewhat greater than its distance from the bottom of the box so as to form two chambers or compartments. Mounted 90 on the under side of the base 6 so as to project into the chamber formed by the space between said base and the box bottom are one or any number of pairs of switch terminals 7—8 (in the present case three) respectively provided with contact clips for the reception of switch blades 9. Each of said blades is pivoted between the clips of one of the terminals 7 and is of such a

length as to removably fit between the clips of the terminal 8 so as to make electrical connection therewith. In the present case the terminals 8 each has fixed to or formed 5 as part of it a projecting portion 10 for the reception of a screw or bolt whereby a cable terminal or other form of electrical conductor may be connected at will.

On the opposite or upper side of the insulating base or plate 6 are mounted a number of pairs of fuse-receiving contacts 12-13, corresponding in number to the number of sets of switch contacts 7-8. Of these fuse contacts, those indicated at 13 are 15 in permanent electrical connection with the switch terminals or contacts 7 by means of screws or other forms of metallic conductors 14, extending through the base 6, and the terminals or contacts 12 have projecting 20 portions 15 for the reception of screws or bolts 16 whereby cable terminals or electrical conductors may be placed in electrical connection with them.

In accordance with my invention, all of 25 the switch blades 9 are mechanically connected by a bar 17 of insulating material extending across them and preferably having at its ends trunnion-like projections 18 designed in the case illustrated, to be detachably engaged by a switch operating member 19. This latter has the form of an elongated strip or plate of relatively stiff metal bent to provide two substantially parallel end portions of unequal lengths projecting 35 substantially at right angles to an intermediate portion which is parallel with the bar 17. Said end portions of the operating member are pivotally connected to the opposite sides respectively of the box 1 by 40 rivets or other equivalent devices 20 and the longer one of said arms extends beyond its pivot so as to project above the plane of the cover 2 when in certain positions although it is movable into a position below this 45 plane.

The side portions of the switch operating member 19 have downwardly elongated edge recesses or slots 21 formed between their pivots and the ends of the intermediate portion, 50 for the reception of the trunnions 18 of the switch blade-connecting bar 17 so as to permit of the operative connection of this latter and the operating member regardless of the fact that the line of the pivots 22 for 55 the switch blades 9 is parallel but not coincident with the line of the pivots 20. The long arm of the operating member extends immediately adjacent one of the sides of the box 1 within the same, and to permit of its 60 projection outside of the box under certain conditions, the cover 2 is formed with an elongated slot 23 having near one end an entrance opening 24.

The switch operating member 19 has an 65 actuating handle 25 projecting in a line sub-

stantially at right angles to the plane of the side of the box and connected to said member by a pin or bolt 26. The side of the box adjacent which said lever operates is formed with a slot or recess 27 projecting downwardly at an angle from and forming a continuation of the entrance opening 24 into the slot 23 of the cover, and the bottom of this recess 27 forms a stop to limit movement of the handle 25 and therefore of the operating member 19 in one direction; the movement in the opposite direction being limited by the engagement of the pin 26 with the edge of the cover 2. This pin also enters a slot in the side of the box so as to prevent 80 its being raised. The arrangement of parts is such that when said handle and therefore the pin 26 connecting its body portion to the switch-operating member 19, rests at the bottom of the recess 27, the movable 85 switch elements formed by the blades 9 are in their open position, i. e.,—out of contact with and distant from the clips of the terminals 8, and on the other hand, when the handle 25 and therefore the switch operating member 19 occupies the other extreme 90 of its path of movement, as shown in Fig. 4, in full lines, so that said pin rests on the edge of the cover 2 adjacent one end of the slot therein, the switch blades 9 are in engagement and make electrical connection with, the switch terminals 8.

According to my invention, the mounting and construction of the switch operating member 19 are such that when it occupies a 100 position corresponding to the closed position of the switch blades, it projects up through the slot 23 in the cover 2 and thus effectually locks it so as to prevent its swinging on the pivot 3. This same condition 105 holds until the switch operating member has been so moved that its upper end lies wholly below the plane of movement of the cover 2 with its pin or spindle 26 resting upon the bottom of the recess 27 in the 110 side of the box, at which time the switch blades 9 in the case shown are disengaged from the switch terminals 8.

As a result of this construction it is manifestly impossible to open the box 1 by movement of the closure 2 as long as the switch is closed, although such opening may be readily accomplished by swinging the cover on its pivot 3 as soon as the switch operating member has been moved to the position shown in dotted lines in Fig. 4, in which the switch blades 9 are out of contact with the terminals 8. Moreover, when said operating member 19 and handle 25 occupy these 115 latter positions, they cannot be moved therefrom as long as the cover 2 occupies any position other than one in which the box is absolutely closed.

In order to prevent said cover 2 being 120 swung so far on its pivot 3 as to free the op- 125

erating handle 25 and permit closure of the switch while the cover was open, the latter has a stop 28 in the form of a projection extending downwardly from its under side at 5 a point adjacent its lug 5, which projection engages the vertical side 29 of the box when the cover 2 has been swung on its pivot sufficiently far to expose the fuse clips or terminals 12 and 13 and permit of the removal 10 or insertion of cartridge or other forms of fuses.

Under conditions of use, one set of the switch terminals 8 are customarily connected to the line or other source of current supply, 15 so that they are at all times "alive," and consequently when the switch is closed current is free to flow through the switch blades 9 to the fuse terminals 13, thence through the fuses 2 to the fuse clips 12 and to any electrical apparatus connected to the terminals 15. When however the switch operating member 19 has been moved to such position as to open the switch, current is thereupon cut off from the fuses and 25 fuse terminals, and since under these conditions said terminals cannot be "alive" or in connection with the switch terminals 8, which are enclosed and protected within the chamber formed by the base or barrier 6, it 30 is obvious that said fuse terminals may be safely exposed and handled without danger. It is therefore under these conditions that the box cover may be freely opened, and in accordance with my invention, it is 35 an impossibility to again close the switch so as to supply current to these fuse terminals without first replacing said cover in its closed position so that access to the fuses or the fuse terminals cannot be had.

40 I claim:

1. The combination in a safety device of a box; a slidable cover therefor having a recess; a switch in the box; and an operating member for the switch having a portion 45 outside the box positioned to extend into said recess of the cover to lock the same closed when the switch is closed.

2. The combination in a safety device of a box; a switch mounted in the box; a handle constituting an operating member for said switch; and a cover for the box formed to prevent movement of the operating member to a position to close the switch except when said cover is in a position to fully close the box, said cover being recessed in the path of movement of the operating member to permit actuation of the latter when said cover fully closes the box.

3. The combination in a safety device of a box; a cover therefor having a recess; a switch in the box; means for actuating the switch including an oscillatory handle positioned to enter the recess of the cover and close the switch only when the cover occupies a box closing position.

4. The combination in a safety device of a box; a cover therefor having a recess; a switch in the box; and operating means for the switch including an arm outside of the box formed to enter the recess of the cover to lock the latter in its box closing position when the switch is closed.

5. The combination in a safety device of a box; a cover therefor having a recess; a switch in the box; and operating means for the switch including an external handle formed to enter the recess of the cover to lock the latter in its box closing position when the switch is closed, said cover being formed to lock said arm in position with the switch open when the cover occupies any position other than one closing the box.

6. The combination in a safety device of a box; a plate of insulating material mounted in said box to divide it into two chambers; a cover for the box movable to permit access to one of said chambers and having a recess; a switch having its movable member in the second of said chambers; fuse terminals in the first chamber; and operating means for the switch including a member positioned to enter the recess of the cover so as to lock the same and prevent access to the fuse terminal chamber while the switch is closed.

7. The combination in a safety device of a box; a plate of insulating material mounted in said box to divide it into two chambers; a cover for the box movable to permit access to one of said chambers and having a recess; a switch having its movable member in the second of said chambers; fuse terminals in the first chamber; and operating means for the switch including a member positioned to enter the recess of the cover so as to lock the same and prevent access to the fuse terminal chamber as long as the switch is closed, said member co-operating with said cover to lock the switch in an open position as long as the cover is open sufficiently to permit of access to the fuse chamber.

8. The combination of a box; a plate of insulating material mounted therein and dividing the interior of the box into two chambers; a switch mounted on the plate within one of said chambers; fuse terminals also mounted on said plate within the second chamber and electrically connected to said switch; a cover for the fuse containing chamber; switch operating means including a member having a portion movable into the path of movement of said cover, the latter being recessed to permit of the member being moved into a position to close the switch and occupying a position, when the fuse chamber is open, to retain said member in a position with the switch open.

9. The combination in a safety device of a box; a switch therein; an operating handle

for the switch pivoted within the box and having a portion projecting outside of the same when the switch is closed; and a cover for the box held from movement by said portion as long as it projects from the box.

10. The combination in a safety device of a box; a switch therein; an operating arm for the switch pivoted within the box and having a portion projecting outside of the same when the switch is closed; and a cover for the box held from movement by said portion as long as it projects from the box, the latter being cut away to permit of movement of the member to a switch opening position, 15 and the cover being externally formed to lock said member in such position when moved to a position to open the box.

11. The combination in a safety device of a box having an opening; a substantially flat cover for the opening mounted to be movable in its own plane and formed with a recess in its external edge; a switch in the box; with an operating member for the switch movable in a plane intersecting the plane of movement of the cover and formed 25 to enter the recess of the latter to lock it from movement as long as the switch is closed.

12. The combination of a box; a recessed plate forming a cover for the box and pivoted thereto; a switch in the box; an operating member for the switch movable at right angles to the plane of movement of said plate and formed to enter the recess 35 thereof when occupying a position corresponding to the closed position of the switch.

13. The combination in a safety device of a box having a recess in one side; a switch in the box; means for operating the switch including an arm projecting outside of the box when the switch is closed and having a handle entering the recess of said box when the switch is open; with a cover for the box having a recess placed to receive said arm, 40 when this is in a switch closing position, said recess at such time communicating with the recess of the box to permit movement of the arm and its handle into and out of a switch opening position.

14. The combination of a box having a

recess in one side; a cover for the box having a slot communicating with said recess when the cover is closed; a switch in the box; means for operating the switch including an oscillatory member movable into the slot of the cover when the latter is closed and held from movement when the cover is open; and a handle for said member formed to lie within the recess of the box when the switch is open.

15. The combination of a box having a recessed cover; a switch having one or more blades pivotally mounted in the box; an operating arm pivoted in the box and operatively connected to said blades, said arm being positioned to enter the recess of the cover when the latter and the switch are closed, while being held by the cover from movement when occupying a position; with the switch open.

16. The combination of a box having a recessed cover; a switch mounted in the box; and a switch operating arm mounted in position for its end to enter the recess of the cover to lock it in place as long as the switch is closed.

17. The combination of a container having a slidable cover; a barrier dividing the container into chambers; a switch in one of said chambers; fuse terminals in the other chamber positioned to be exposed when the cover is open; and switch-operating means including a handle projecting outside of the container and positioned to lock the cover closed until the switch is opened.

18. The combination of a container having a slidable cover; an insulating base therein; a switch mounted on and enclosed within the container by said base; terminals positioned on the base to be accessible when the cover is in an open position; and means for controlling the switch including a swinging operating arm interposed in the path of movement of the cover when this is in its closed position and the switch is closed, said arm releasing the cover when moved to a switch-opening position.

In witness whereof I affix my signature.

WILLIAM T. PRINGLE.
